BRACE FOR DOORS AND THE LIKE

James H. Boye, Chicago, Ill., assignor to James H. Boye Manufacturing Company, Chicago, Ill., a corporation of Illinois

Application July 19, 1946, Serial No. 684,672

3 Claims. (Cl. 20—38)

1

The invention relates to anti-sag attachments for screen doors and such other doors as have a tendency to sag and has for an object to provide an improved device for application to such doors for the purpose of bracing the same to thereby remove and eliminate sagging which such doors readily develop following extended periods of use.

A diagonal bracing rod with turnbuckle adjustment for lengthening or shortening the rod has generally been used to remove and eliminate sagging in doors particularly of the screen type wherein the frame includes a plurality of jointed members. Such bracing is visible and is otherwise objectionable. The improved attachment of the invention is invisible since it is applied to the upright frame and center cross-bar members, and in addition to performing an anti-sagging function the present attachment also serves to reinforce the cross-bar member and to rigidly join the same to the frame of the door.

Another object of the invention resides in the provision of an anti-sagging and bracing attachment for screen doors which can be used on either right or left swinging doors.

A further object resides in the provision of an anti-sagging attachment for the purposes described which will incorporate an adjusting screw for selectively adjusting the attachment to thereby elevate the door to the extent necessary for removing the sag in the door.

With these and various other objects in view, the invention may consist of certain novel features of construction and operation as will be more fully described and particularly pointed out in the specification, drawings and claims appended hereto.

In the drawings which illustrate an embodiment of the invention and wherein like reference characters are used to designate like parts—

Figure 1 is a front elevational view of a screen door with the attachment of the invention applied thereto as contemplated by the invention;

Figure 2 is a sectional view through the attachment substantially along line 2—2 of Figure 1; and

Figure 3 is a sectional view illustrating the action of the adjusting screw taken substantially along line 3—3 of Figure 2.

The invention as illustrated in the drawings is applied to a screen door such as 10 including the upright frame members 11 and 12 and which are suitably joined to the transverse frame members 13 at the top and 14 at the bottom. The cross-bar member 15 is located substantially midway of the door and forms the third transverse member, all

2

of which have a jointed connection with the upright frames 11 and 12. The door 10 has hinges 16 attached to the upright frame 11 and accordingly any sag will occur with respect to the upright member 12 and the respective transverse members. For bracing these members the attachment of the invention is applied as shown in Figure 1, the same being invisible from the outside and also having the effect of joining cross-bar member 15 to the hinged upright 11.

The attachment essentially comprises a leverage arm 18 in the form of a channel bar as is clear from Figure 2 and which bar is secured at one end to the upright member 11 and at its other end to the cross-bar member 15 as by screws 19. This channel bar, preferably formed of any suitable metal, therefore joins or unites these two members and functions as a brace to rigidly connect them and reinforce the jointed construction. A fixed metal abutment plate 20 is associated with the leverage arm and said plate is secured in proper position on the upright frame member 11 by the securing screws 21. Said proper position locates the plate over the leverage arm, the plate being of channel shape for the purpose and thus clearance is provided for an auxiliary or wear plate 22, all as shown in Figure 2. The wear plate is located between the abutment member 20 and leverage arm 18 and is in the shape of an L so as to include an upright leg and a horizontal leg. The horizontal leg is disposed under and in contact with the channel bar 18, whereas the upright leg has a rivet 23 fixed thereto and which operates in the vertical slot 24 in the abutment member. The plate 22 is therefore connected to member 20 with provision being made for vertical movement of the wear plate with respect thereto.

Adjustment of the attachment is provided for by an adjusting screw 25 which is threaded in the bottom flange or ledge 26 of the abutment member 20, the said ledge being present by reason of the channel shape of the member. Since the ledge is of thin metal the threaded connection of the screw 25 is preferably supplemented by a nut 27 which may or may not be welded or soldered to the ledge. In any event, the nut 27 is supported by the ledge and is held against turning so that rotation of the screw will move the same vertically toward or away from the horizontal leg of the wear plate 22.

By employing an auxiliary or wear plate such as 22 the height of the channel bar 18 is held to a minimum. The horizontal leg of said plate overlies the screw 25 and provides a contact member therefor since the screw engages said

member, that is, the horizontal leg of the plate, and through the plate applies an upward thrust to the channel bar. If the auxiliary or wear plate were omitted it would be necessary to increase the height of the channel bar in order to insure adequate contact of the screw therewith. This would be more expensive in that more metal would be used and it would also give the device a heavy appearance. Therefore the present construction is relatively economical to manufacture, a sturdy and streamlined appearance is presented, and the device functions very satisfactorily as a bracing attachment for doors.

The various elements comprising the present attachment as above described are associated with each other and with a door as shown in Figure 1. The abutment plate 20 is fixedly secured by the screws 21 to the upright frame member 11, which member has connection with the hinges 16 and may be referred to as the hinge member of the screen door. The bar 18 underlies the abutment plate and it will be clearly seen that the adjusting screw 25 has operative contact with said bar 18 through the medium of the wear plate 22. By adjusting the screw 25 the bar 18 is caused to act as a leverage bar, pressure from the adjusting screw being applied thereto to elevate the right hand end of the bar, Figure 1, and maintain the same elevated, thereby eliminating any sag which may develop in the screen door. The left end of bar 18 is fixedly secured by screw 19 to the upright 11 as has been described. The right hand end of said bar 18 is similarly secured to the cross bar member 15 by the screw 19a. The abutment plate 20 and adjusting screw 25 act to apply pressure to bar 18, causing the same to perform as a leverage bar and maintain cross bar 15 in elevated position to prevent the screen door from sagging. The extent of adjustment of bar 18 may be varied by adjusting screw 25. Rotation of the screw in one direction will affect a lowering of the bar 18 in which event the same will rotate in a clockwise direction, Figures 1 and 3, having rotary movement around screw 19 as an axis. Rotation of adjusting screw 25 in the other direction will function to elevate bar 18, in which case the bar will have rotary movement in a counter-clockwise direction around screw 19 as an axis. Limited adjustment of the bar 18 will be sufficient to counter any sagging tendency which the door may develop and the attachment will in addition have the desirable function of reinforcing the cross-bar member for rigidly joining the same to the frame of the door.

The invention is not to be limited to or by details of construction of the particular embodiment thereof illustrated by the drawings as various forms of the device will of course be apparent to those skilled in the art without departing from the spirit of the invention or the scope of the claims.

What is claimed is:

1. In a bracing attachment for such doors as have substantially vertical frame members and transverse members, in combination, a channel bar adapted to be secured at one end to one of said vertical frame members of the door and at its other end to a transverse member thereof and being disposed substantially parallel to the transverse member, an abutment member substantially channel-shaped in cross section also having secured to said vertical frame mem-

ber in associated relation with the channel bar whereby said abutment member overlies the channel bar, a wear plate connected to said abutment member in a manner permitting limited movement of the plate vertically of said abutment member, said plate being interposed between the abutment member and the channel bar, and an adjusting screw carried by the abutment member and positioned under the channel bar, said adjusting screw having operation to contact the wear plate and through the medium of said plate to apply pressure to the channel bar whereby to eliminate and prevent sagging of the door.

15 2. A bracing attachment for such doors as have a substantially vertical hinge member forming one of the side frames of the door and transverse members connected to said hinge member, in combination, a leverage bar substantially channel-shaped in cross section adapted to be secured at one end to the hinge member and at its other end to one of said transverse members and being disposed substantially parallel to the transverse member, an abutment member also substantially channel-shaped in cross section and adapted to be secured to the hinge member, said abutment member when in secured position overlying the leverage bar intermediate its ends and being independent thereof, a wear plate carried by the abutment member and interposed between said member and the leverage bar, and an adjusting screw carried by the abutment member and positioned below the leverage bar but adapted to engage the same indirectly through the wear plate, whereby pressure may be applied to the leverage bar in an upward direction by adjustment of the screw for eliminating and preventing sagging of the door.

30 3. In a bracing attachment for such doors as have a substantially vertical hinge member forming one of the side frames of the door and transverse members connected to said hinge member, in combination, a leverage bar substantially channel-shaped in cross section and adapted for 35 securing at one end to the hinge member and at its other end to the transverse member and being disposed substantially parallel to the transverse member, an abutment member also substantially channel-shaped in cross section and adapted to be secured to the hinge member, said abutment fulcrum member when in secured position overlying the leverage bar intermediate its ends and being independent thereof, a wear plate connected to the abutment member in a manner permitting limited vertical movement of the plate, said plate having a horizontal leg located under the leverage bar and providing a contact and wear member for the bar, and an adjusting screw carried by the abutment member and adapted to contact the horizontal leg of said plate whereby to apply upward pressure to the leverage bar to hold the bar in desired adjusted position.
